DUPLICATING MACHINE

Charles H. Bradt, Groton, N. Y., assignor to L C
Smith & Corona Typewriters, Inc., Syracuse,
N. Y., a corporation of New York

Application March 12, 1937, Serial No. 130,480

13 Claims. (Cl. 101—133)

This invention relates to improvements in duplicating machines, and more particularly to duplicating machines of the hectograph type.

In duplicating machines of the hectograph type it is a common practice to lay and impress the master and copy sheets upon the surface of the resilient gelatinous or other duplicating medium by means of a sheet laying and impression roller or platen roller mounted in a traveling carriage. Considerable difficulty has been had in transferring a uniformly inked and undistorted negative impression from a master sheet to the gelatin surface, in transferring a uniformly inked and undistorted positive impression from the gelatin surface to a copy sheet, in compensating for variations in thickness of sheets impressed upon the gelatin, and in preventing rupture of the gelatin by excessive pressure thereagainst. The present invention has for its principal object to provide improved supporting and guiding means for the carriage, and particularly to provide simple and effective means for so supporting and guiding the carriage as to overcome the above difficulties, obtain excellent impressions irrespective of variations in level of the gelatin surface and variations in thickness of a sheet, and avoid liability of rupturing the gelatin duplicating medium or composition.

Other objects and advantages of the invention will appear from the following description of the preferred embodiment of the invention illustrated in the accompanying drawings, and it is a purpose of the invention to obtain any and all advantages with respect to structure and to operation which are inherent in the construction shown in the drawings as constituting the preferred embodiment of the invention.

In the drawings, in which so much of a duplicating machine of the hectograph type is shown as is necessary to an understanding of the present invention:

Fig. 1 is a fragmentary side elevation of the machine, the traveling carriage being shown positioned adjacent the front end of the machine with the impression or platen roller lowered to working position;

Fig. 2 is a fragmentary plan view of the machine, with the parts positioned as in Fig. 1, a part of the machine frame being shown broken away;

Fig. 3 is a detail fragmentary front elevation of the machine showing the carriage mounting;

Fig. 4 is a detail fragmentary plan view showing the carriage mounting;

Fig. 5 is a detail sectional view on the line 5—5 of Fig. 4;

Fig. 6 is a detail sectional view taken on the same line as Fig. 5 and showing on an enlarged scale certain of the parts illustrated in Fig. 5; and

Fig. 7 is a view similar to Fig. 5, but showing the carriage swung upward and to the right from its working position shown in Figs. 1 to 6 into an inoperative position in which the carriage is supported up-ended at the right hand side of the machine to facilitate access to the bed of the machine and the gelatin medium stretched over the bed.

The machine has a suitable frame 10 which supports a flat horizontal bed 11 and includes two flat horizontal tracks 12 and 13. The tracks extend longitudinally of the bed fore and aft of the machine at the right and left hand sides or edges of the bed. The usual gelatin duplicating band 14, connected at its ends as usual to winding spindles 15 journaled in the frame, is stretched over and rests upon the bed 11 with the usual resilient gelatin coating of the band uppermost where the band lies upon the bed.

Reciprocable over the bed longitudinally of the bed or fore and aft of the machine is an impression roller carriage 16 in which is journaled at 17 the usual pivoted yoke 18 provided with the usual operating handle 19 and having journaled in its rearwardly extending arms at 20 the usual impression roller or platen roller 21 by which the sheets are laid and impressed upon the gelatin surface of the duplicating band 14. Fixed to the carriage is the usual paper feed table 22, and there is also preferably mounted in the carriage the usual paper feed roller 23 between which and the platen roller a sheet is fed in the usual manner from the paper table. Any suitable known mounting for the usual feed roller 23 may be provided, such as that shown in my Patent No. 1,983,517, granted December 11, 1934. Rearward thrust on handle 19 lowers platen roller 21 relatively to the carriage to its working position in the carriage, which position is that shown in Figs. 1 and 2 and is determined by suitable stops 34 on the carriage which are engaged by the yoke to limit the extent of lowering movement of the roller 21 relatively to the carriage. Forward pull on the handle elevates the roller 21 in the carriage to inactive position.

The features above described are known and the improvements will now be described.

At its right hand end the carriage 16 is formed with a pair of parallel arms 24 spaced apart fore-and-aft of the machine and which, when

the carriage lies over the bed, curve outwardly and downwardly around track 12 to a point below and outside of said track. These arms are connected by an upstanding flat web or plate 25, 5 preferably formed integrally with the arms as shown, said web being disposed substantially vertically edgewise when the carriage overlies the bed in working position, as shown.

A horizontally disposed guiding and supporting cylindrical rod 26 for the carriage is fixedly and stationarily held at each end of said rod to the machine frame 10 in any suitable manner, such as that shown at 27, for example, with said stationary rod extending fore-and-aft of the machine parallel to and below track 12 and parallel to the adjacent right hand longitudinal side edge of the bed 11.

Mounted on rod 26 to slide thereon and to rotate thereabout about the axis of the rod is a yoke comprising a pair of parallel side arms 28 formed integrally with a cross member or connecting member 29, which latter member is curved or bowed to partly encircle the rod and is provided at one longitudinal edge thereof with an abutment face 30, and is provided at the other longitudinal edge thereof with a central arm or extension 31 having an abutment face 32 parallel or approximately so to abutment face 30, the two abutment faces being at opposite sides of rod 26 and facing in the same direction. Arms 28 are rotatively and slidably journalled on rod 26 adjacent to connecting member 29 and have their outer ends connected by suitable horizontal pivots or journals 33 to the outer lower ends of the arms 24 of the carriage, so that the carriage may pivot relatively to the yoke about a horizontal axis whose level varies with the rocked position of the yoke 28-29 about rod 26.

40 Plate or web 25 integral or rigid with the carriage is provided adjacent its lower edge with an abutment face 35 opposed to abutment face 30 of the yoke 28-29. Fixedly held to web 25, and extending therethrough at a right angle thereto and adjacent the upper edge thereof, is a housing 36 the inner end face 36^a of which constitutes an abutment face opposed to abutment face 32 on the yoke 28-29. The relation of the abutment faces 30 and 32 on the yoke 28-29 to the abutment faces 35 and 36^a on the carriage are such as to permit a limited rocking or pivotal motion between the carriage and said yoke, as shown, that is faces 30 and 35 cannot contact at the same time as faces 32 and 36^a. Normally 55 in the working position of the carriage both the pair of opposed faces 32 and 36^a and the pair of opposed faces 30 and 35 are yieldingly held out of contact by resilient means the force of which is adjustable. This resilient means comprises a spring-pressed plunger the head 37 of which slides in the reduced inner end portion 38 of an axial bore in the housing 36. The plunger has a stem 39 telescopically slidable in a bore 40 in the head and encircled by a coiled spring 41, which spring abuts with its ends the adjacent or opposed ends of the head of the plunger and an externally threaded head 42 formed on the stem 39 and screwed into the internally threaded enlarged outer end portion 43 of the bore of housing 36. It will be obvious that, by screwing head 42 more or less into the threaded portion 43 of housing 36, the effect of spring 41 on the plunger head may be varied. Spring 41 70 normally holds the plunger head partly pro-

truded from housing 36 with the rounded end of the head pressed against abutment face 32.

At its right and left hand sides or ends the carriage has journalled thereon for rotation about coincident axes the two supporting wheels 5 or rollers 44 whose journals are so located that said wheels overlie tracks 12 and 13 in the working or bed overlying position of the carriage. The level of the journals on the carriage is such, however, that said wheels rest on or contact the tracks only when the platen roller 21 is lifted out of working position or contact with the gelatin or a sheet lying on the gelatin, and is such that lowering of the roller 21 into working position with yoke 18 against stops 34 lifts the rollers 15 44 off the tracks as shown in Figs. 1, 3 and 5. Rollers 44 and tracks 12 and 13 are thus effective to support the carriage out of contact with the gelatin band while roller 21 is lifted in the carriage but have no such effect when the roller 20 21 is lowered in the carriage to working position.

When roller 21 is in working position the carriage is supported in part by the contact between roller 21 and the gelatin band or a sheet (master sheet or copy sheet) interposed between the gelatin band and roller during sheet laying and impressing travel of the carriage and roller 21 rearward over the bed from the starting position for such laying and impressing shown in Figs. 1 and 2, and said carriage is also supported in part 30 through the connections described above between the carriage and rod 26, the latter connections serving also to guide the carriage. It will be obvious that spring 41 sustains part of the weight of the carriage and of the parts mounted thereon, 35 including the platen roller, and also that the percentage of the total weight taken off the gelatin band may be varied by screwing the plunger stem 39-42 more or less into housing 36. It will thus be observed that the carriage is more or 40 less resiliently supported through its connection with the machine frame during sheet laying and impressing operations thereof and that the spring support may be varied, thereby permitting variation of the load on the gelatin to enable attaining 45 like intensity of ink transfer with sheets of different thickness and, if desired, heavy or light impressions on sheets of equal thickness.

It will also be observed that the carriage mounting is such that the carriage may float up 50 and down substantially in parallelism with the bed and may also teeter transversely of the bed, so that the impression roller may follow variations in surface height whether the variations are longitudinal or transversely of the bed, thus 55 greatly contributing to uniformity of pressure of the roller on all parts of a surface over which it is traversed.

The carriage mounting is also such that the carriage may be up-ended at one side of the bed 60 as shown in Fig. 7, to afford free access to the bed when desired, as, for example, when it is desired to change the duplicating band. It will be obvious that, if the carriage is lifted upward and rightward, face 35 will quickly contact face 65 30 and that the carriage and yoke will, thereafter, swing as a unit about rod 26. In order that the carriage may stand up-ended without having to be held up by the operator, the machine frame is provided with a ledge or flange 70 45 lying below and to the left of rod 26 in a horizontal plane and extending at least substantially the full length of said rod, the outer edge of which flange forms an abutment face which is contacted by an abutment face 46 on the web 75

or plate part 25 of the carriage after the carriage has been swung upward and rightward slightly beyond a perpendicular position, as shown in Fig. 7. The carriage may thus be 5 ended at any point of its travel and into a position in which it will remain until it is purposely rocked back toward working position.

What I claim is:

1. In a duplicating machine of the hectograph type, the combination of a bed for supporting the duplicating medium, a single guide rod fixedly related to said bed, a support held to said guide rod to slide longitudinally of the rod and to rotate about the rod, a platen roller supporting carriage hinged to said support to swing relatively thereto about an axis parallel to the rod, and means interposed between said carriage and support to yieldably resist swinging movement between the carriage and support in the direction permitting approach of the carriage to the bed.
2. In a duplicating machine, the combination of a frame, a bed thereon, a hectograph duplicating medium overlying and backed by the bed, a platen roller carriage, a guide rod for the carriage supported in fixed relation to the bed and extending longitudinally of the bed, means connecting one end of the carriage to said guide rod to constrain the carriage to travel longitudinally of the bed and permit the carriage to rise and fall substantially perpendicularly to the bed and also teeter transversely of the bed with the carriage extending transversely of and overlying the bed and duplicating medium, a platen roller extending between the ends of the carriage and mounted in the carriage for lowering of said roller to and lifting thereof from a predetermined working position in the carriage in which the carriage is supported above the bed and duplicating medium through said roller and said connecting means, said connecting means including spring means by which said connecting means yieldingly sustains part of the weight of the carriage while the carriage is supported through both said roller and connecting means.
3. In a duplicating machine, the combination of a frame, a bed thereon, a hectograph duplicating medium overlying and backed by the bed, a platen roller carriage, a guide rod for the carriage supported in fixed relation to the bed and extending longitudinally of the bed, means connecting one end of the carriage to said guide rod to constrain the carriage to travel longitudinally of the bed and permit the carriage to rise and fall substantially perpendicularly to the bed and also teeter transversely of the bed with the carriage extending transversely of and overlying the bed and duplicating medium, a platen roller extending between the ends of the carriage and mounted in the carriage for lowering of said roller to and lifting thereof from a predetermined working position in the carriage in which the carriage is supported above the bed and duplicating medium through the medium of said roller and said connecting means, said connecting means including spring means by which said connecting means yieldingly sustains part of the weight of the carriage while the carriage is supported through both said roller and connecting means, and means on the carriage and frame engageable in all positions of travel of the carriage to support the carriage and roller out of contact with the duplicating medium only while the roller is lifted out of its working position, said

engageable means being separated by lowering of the roller to working position in the carriage.

4. A duplicating machine having, in combination, an upwardly facing bed, a duplicating medium stretched over the bed, a platen roller supporting carriage, a platen roller in the carriage, a guide rod for the carriage extending longitudinally of the bed adjacent and parallel to one longitudinal edge of the bed and supported in fixed relation to said bed, and means connecting one end of said carriage with said guide rod to permit reciprocation of the carriage and roller longitudinally of the bed over the bed and medium with the carriage and roller extending transversely of the bed and to permit said carriage and roller to move substantially perpendicularly to said bed and also to teeter transversely of the bed during such reciprocation with part of the weight of the carriage yieldingly transmitted through said connecting means to said fixedly supported guide rod and the remainder of the weight of the carriage transmitted to the duplicating medium and bed through said platen roller.

5. A duplicating machine having, in combination, an upwardly facing bed, a duplicating medium stretched over the bed, a platen roller supporting carriage, a platen roller in the carriage, a cylindrical guide rod for the carriage extending longitudinally of the bed adjacent and parallel to one longitudinal edge of the bed and supported in fixed relation to said bed, rigid means slidably and pivotally held to said rod and hinged to one end of the carriage for hinge movement therebetween and the carriage about an axis parallel to the rod, resilient means interposed between said rigid means and the carriage and coactive therewith to permit reciprocation of the carriage and roller over the bed longitudinally of the bed with the carriage and roller extending transversely of the bed and with said carriage yieldingly urged upwardly by said resilient means and said rigid means.

6. A duplicating machine having, in combination, an upwardly facing bed, a duplicating medium stretched over the bed, a platen roller supporting carriage, a platen roller in the carriage, a guide rod for the carriage extending longitudinally of and parallel to the bed and supported in fixed relation to said bed, rigid means slidably holding the carriage at one end to said rod for movement of the carriage about two parallel axes one of which is coincident with the rod axis, said means permitting reciprocation of the carriage and roller over the bed with the carriage and roller extending transversely of the bed, and spring means interposed between the carriage and said rigid means to tend to lift said end of the carriage during reciprocation of the carriage and roller over the bed with the carriage and roller overlying and extending transversely of the bed.

7. A duplicating machine, as claimed in claim 4, having means adjustable at will to vary the proportion of the weight of the carriage sustained by said connecting means between the carriage and guide rod.

8. A duplicating machine, as claimed in claim 6, having means adjustable to vary the lifting force exertable by the spring means on the carriage.

9. A duplicating machine, as claimed in claim 4, wherein said connecting means permits upwarding of the carriage at said longitudinal edge of the bed.

10. A duplicating machine, as claimed in claim 5, having abutment means on the carriage and said rigid means for limiting the hinge movement therebetween, and having fixed means coactive with said carriage and said rigid means in 5 all positions of travel of the carriage along the bed to permit swinging of the carriage and said rigid means about the guide rod and arrest such swinging when the carriage reaches an up-ended 10 position in which it will remain until positively reversedly swung therefrom.

11. A duplicating machine having, in combination, a frame, an upwardly facing bed fixedly supported thereon, a duplicating medium extending 15 over and resting on the bed, a platen roller carriage, a cylindrical guide rod for the carriage supported in fixed relation to the bed with said rod extending longitudinally of and parallel to the bed, rigid means slidably and pivotally held 20 to said rod for travel along the rod and turning about the axis of the rod, means pivotally connecting said rigid means with one end of the carriage for a slight positively limited hinge movement between said rigid means and carriage 25 about an axis parallel to the axis of the rod with the carriage and rigid means folded upon each other and with the carriage extending across the rod to said hinge connection, means on the carriage and frame engageable at opposite longitudinal 30 sides of the bed to support the carriage for travel over the bed longitudinally of the bed out of contact with the duplicating medium, a platen roller mounted in the carriage to extend transversely of the bed when the carriage is supported

by said engageable means and for movement in the carriage toward and from the bed to separate and permit engagement of said engageable means while the carriage is positioned over the bed, and resilient means interposed between the 5 rigid means and carriage to exert a lifting force on the carriage while the carriage is positioned over the bed.

12. A duplicating machine, as claimed in claim 11, wherein the carriage may be up-ended, at 10 any position of its travel along the bed, through its connection with the guide rod, and the frame carries stationary means engageable by the carriage when the latter is up-ended at any point 15 in its travel to support the carriage in up-ended position through its connection with the guide rod.

13. A duplicating machine having, in combination, an upwardly facing bed, a duplicating medium extending over and resting on the bed, 20 a cylindrical guide rod supported in fixed parallel relation to one edge of the bed, a platen roller for impressing sheets on said medium, a carriage for said roller, a support slidably and pivotally held to said rod, and a spring-hinge 25 connection between said support and one end of the carriage holding said carriage to the support with the carriage extending across the rod to said hinge connection, the axis of which connection is parallel to the rod axis, said support and spring-hinge connection resiliently transmitting part of the weight of the carriage to the guide rod.

CHARLES H. BRADT.
